OTTO PETERMANN, OF NEW YORK, N. Y., ASSIGNOR, BY MESNE ASSIGNMENTS, TO CORONA TYPEWRITER COMPANY, INCORPORATED, A CORPORATION OF NEW YORK.

FEED MECHANISM FOR TYPE-WRITING MACHINES.

1,121,033.

Specification of Letters Patent. Patented Dec. 15, 1914.

Application filed July 7, 1909, Serial No. 506,442. Renewed October 8, 1914. Serial No. 865,774.

To all whom it may concern:

Be it known that I, OTTO PETERMANN, a citizen of the Republic of Switzerland, and a resident of New York, county and State of New York, have invented certain new and useful Improvements in Feed Mechanism for Type-Writing Machines, of which the following is a full, clear, and exact description.

10. This invention relates more particularly to the feed mechanism of foldable front strike or visible typewriting machines.

One object of the invention is to provide a simple and efficient machine in which the platen, carriage, and escapement mechanism may be moved vertically to adapt each type-head to have a plurality of characters thereon, and the parts so arranged that they may be folded over above the keys to cause the same to occupy less space than when in use for transportation and other purposes; to provide a machine which is very simple and strong in construction; to provide a machine which may be made very light, and while not taking up very much space when folded it still has the appearance of a large machine when in use, and to provide a machine in which the parts are readily accessible for repair or other purposes.

20. Another object of the invention is to provide a simple and efficient escapement and feed mechanism for the carriage to adapt the carriage to be moved for letter spacing when the key-levers or the spacing bar are operated, and to so construct the said feed mechanism that certain parts thereof may be separable to adapt the carriage and platen to be shifted into a compact relation with another part of the machine when not in use.

25. A further object of the invention is to provide simple and efficient means whereby certain of the escapement parts may be released from each other to permit the carriage to move freely and quickly in the direction of letter spacing, or to permit the carriage to be moved freely backward without operating all the parts of said mechanism.

30. With these and other objects in view, the invention will be hereinafter more particularly described with reference to the accompanying drawings, which form a part of

this specification, and will then be pointed out in the claims at the end of the description.

In the drawings, Figure 1 is a longitudinal section, partly in elevation, of one form of machine embodying my invention. Fig. 2 is a detail vertical section of a part of the feed mechanism. Fig. 3 is a rear elevation of the machine, a part thereof being broken away to more clearly illustrate certain features of the machine. Fig. 4 is an inverted plan view of the carriage support and escapement mechanism. Figs. 5 and 6 are views of parts of the escapement mechanism. Fig. 7 is a detail plan view of the propelling drum, partly broken away, to which is held a flexible connection for drawing forward the carriage; and Fig. 8 is an elevation partly in section, showing the spring actuated drum of the propelling mechanism.

The machine hereinafter set forth is of the type shown in the patent to Frank S. Rose, No. 754,242, patented March 8th, 1904, in which the carriage is adapted to be folded over above the keys, and while in the present invention the carriage and platen and their operating mechanisms are adapted to be raised and lowered on the frame of the machine and to be folded over above the finger keys, and in which the type-bars have a front strike for visible writing, it is to be understood that many of the features of this invention may be used in connection with other classes of machines.

The metallic frame 1 of the machine is constructed and arranged in any suitable manner, and may consist of side members 90 and an integral back member with an intermediate transverse horizontal bar 2 suitably fastened to the sides of the frame and serving as a brace therefor, and a second transverse bar 2^a at the front of the machine, the whole frame being constructed of sheet metal with rounded edges for the purpose of making the frame light and strong.

The key-levers 3, Fig. 1, may have keys or finger-pieces 4 forming a part of a universal keyboard, and are each provided intermediate its end with an upwardly-extending part 5. This part 5 forms a head or suspending member which engages the transversely-extending bars 14 located under the plate 2 and which serve to pivotally sup-

port the said key-levers. These levers are each forced in one direction by a spring 16, one end of which is held to a transverse bar 18 and at their inner ends the said levers are connected by links 19 to the type-bars 20. Each type-bar is pivotally held at 21 to a bracket 23 and at its outer end is provided with a type-head 29 having characters 30, 31, and 32 thereon which are adapted to be forced against the platen 35 in the usual or in any preferred way.

Any suitable platen and means for supporting the same may be employed. As shown the platen 35 is of the usual form and is mounted at its ends to rotate in the frame 36 of a carriage 37. The carriage 37 moves along the normally fixed member, bed or support 38, and has a member 39 movable with the carriage which is opposed to the fixed support or bed 38. The member 39 is provided with grooves lengthwise thereof at its under side, as at 40, and the support 38 is provided with grooves 41 on its upper surface opposed to the grooves 40 so as to form race-ways on opposite sides of said member, and in the race-ways are arranged balls 42 forming a bearing for the member 39 of the carriage. As shown there are two balls in the outer race-way, and one in the inner race-way, and each ball may be held in a circular guide 43 which surrounds the same, and normally rests on the member 38 adjacent to the grooves forming a part of each race-way, said guides being connected together by a wire 43^a to hold the balls properly spaced apart and to move together. The carriage 36 is provided with suitable guides, as for example headed studs not shown, and substantially L-shaped brackets or gibs 45 and 46 are also fastened to the fixed member 38, the said bracket 46 being provided with an adjustment screw 47 extending over the member 39 of the carriage as shown best in Fig. 1. The carriage when released, as will be hereinafter described, is moved forward for letter-spacing by a spring 48 arranged in a drum 49, Figs. 1, 7 and 8, one end of which is held to a disk 51 by which the spring may be wound, and the other end to the drum 49, and both the drum and disk are rotatably supported on a shaft 52 over a bracket 53. The disk 51 is provided with finger parts 54 and to said disk is pivoted a pawl 55. This pawl 55 is provided with two teeth 56 and 57, the latter of which is on a handle portion 58 of said pawl, and both teeth are adapted to engage a fixed ratchet wheel 59, by which said disk may be held in an adjusted position and released by a step-by-step movement as desired. A flexible connection 59^a is carried by the drum and is held at one end to the drum 49 and its other end extends from the drum around a pulley or sheave located on the bed or support of the carriage, and its other end is fastened to

the carriage so that when the carriage is released the tension of the spring will force the same along said bed or support.

The parts thus far described may be of the character shown or of any preferred form.

As a means for letter-spacing the carriage, I employ a special construction of escapement, also a certain kind of escapement in connection with a special kind of typewriting machine. As shown the carriage is provided with a rack-bar 70 which extends lengthwise of the carriage and meshing with said rack-bar is a pinion 71, Fig. 1, and this pinion is held to rotate on a shaft 72 projecting under the carriage bed or support 38 to the lower end of which is held a ratchet wheel 73. This ratchet wheel 73 forms a part of the escapement mechanism and is located above the bracket or plate 73^a in which one end of the shaft 72 is journaled, the ratchet wheel 73 being held to rotate with the shaft 72, and adapted to engage the ratchet wheel is an escapement device or lever 74. This lever or device 74 comprises two parts or members 75 and 76, and carried by the member or part 76 are the pawls or dogs 77 and 78 the former of which is fixed and the latter loose, and said pawls are adapted to alternately engage the teeth of the ratchet wheel 73 to permit said ratchet wheel to rotate with a step-by-step movement. The carriage is moved in one direction by the spring 48 and the movement of the carriage transmits a rotary movement to the ratchet wheel 73 through the rack-bar 70 and pinion 71. The member 76 of the escapement lever is forced in one direction by a spring 76^a, and said escapement lever is pivoted intermediate the ends thereof at 79 to move horizontally above the bracket 73^a. By constructing the lever 74 and arranging the pawls or dogs as shown, the said pawls are caused to move directly into and out of engagement with the ratchet wheel without a sliding movement, thus materially overcoming the wear and effecting a better alignment in letter-spacing. The pawl 78 is pivoted at 80, and is normally forced against a pin 81 by means of a spring 83 and may be limited in its movement by a screw 84 so as to be properly confined in its movement between the end of said screw and said pin 81. The member 76 is normally forced to cause the pawl 78 to engage a tooth of the ratchet wheel 73 by means of the spring 76^a one end of which is fastened to the bracket 73^a and the other end to said member, there being a small flat spring 84^a, Fig. 5, having its free end extending in the path of said ratchet wheel to prevent backward movement or back lash of said wheel. The escapement device or lever 74 is curved or circularly formed to partly encompass the ratchet wheel and at its end opposite the pawl 78 is 130

engaged by the end of the member 75 so as to move the member 76 on its pivot. The member 75 has its end 85 projecting in the path of a movable bar or device 86 to be hereinafter referred to, and as said bar 85 is moved it will force the member 76 on its pivot 79. The member 75 is pivoted at 86^a, Figs. 5 and 6, to the bracket 73^a and has one end hooked and engaging one end of the member 76 to shift the latter when moved vertically, the normal position of the end 85 of said member 75 being downward. As will be seen when the escapement lever is moved, the ratchet wheel, through the action of the spring 48 which forces the carriage in one direction, will rotate the distance of one tooth at each movement of the escapement device or lever 74.

The carriage may be released in various ways. As shown the clutch member 89 of the carriage feed mechanism and escapement is slidingly held on the hub of the pinion 71 and rotates therewith and is provided with a flange 125, and this flange is adapted to be engaged by an arm 126 of an angular slide 127 which is guided in the bracket 46, the said clutch member being normally forced into engagement with the clutch member 88 by a spring 127^a. The angular slide 127 is provided with a pin 128, and this pin is adapted to be engaged by a horizontally movable bar 129. This bar 129 extends transversely at the rear of the carriage, Figs. 1 and 3, and is held in slots in the carriage frame, and said bar is normally forced one way by a spring 130, Fig. 3, and has cam portions 131 which when forced by the finger or otherwise will have an upward movement so as to raise the angular slide 127 and release the clutch member 89 from the escapement mechanism, so that the carriage may be automatically forced forward independently of its feed the desired distance instead of by a step-by-step movement, the clutch permitting the carriage to move backward at all times.

The bracket 169 is held to the rocking rod 169^a and is extended at 170, and the inner end of said bracket is adapted to rest under the bar 86, the latter being forced normally into engagement with the bracket by means of a spring 171. This bar 86 is provided with a plurality of teeth 172, which form abutments adapted to be engaged by a tooth 173 carried by the lower end 174 of an angular lever or arm 175, the said arm being pivoted at 176 to the transverse bar 2 which supports the key-levers. The part 174 is notched at 177 and engaging the notch is a vibrating universal bar 178 which extends transversely of the machine across and over each of the levers and is pivotally held to swing upward and downward. As will be seen when any of the key-levers are depressed, the universal bar will be operated

and this will operate the lever 175, and by reason of the tooth 173 will operate the vertical bar 86 to vibrate the ribbon and also operate the escapement lever. By reason of the teeth in the lower end of the bar 86, the tooth 173 of the lever 175 will engage said bar 86 no matter what position the carriage may be in as the said bar is elevated by both of the shift keys through the rod 168^a and bracket 169 according to which lever is operated, said shift levers being both operatively connected to rock the rod 169^a but not to the same degree. The universal bar 178 is also operated by the spacing levers 178^a which have the usual finger bar, and are each provided with upwardly projecting hooked portions 178^b which engage the transverse bar 2 and pivotally support said space levers. In this application many of the features shown and described are not claimed herein, but form subject matter of other pending applications. The ribbon mechanism is claimed in my pending application Serial No. 501,854, filed June 21, 1909; the platen shift in my application Serial No. 501,850, filed June 12, 1909; the keyboard in my Patent No. 1,081,140, dated December 9, 1913; the bar mechanism in my Patent No. 1,087,459, dated February 17, 1914, and other features in other patents or pending applications filed by me.

From the foregoing, it will be seen that simple and efficient means are provided as an escapement and feed mechanism for the carriage and platen; that simple mechanism is provided whereby the carriage may be shifted into compact relation to another part of the machine when not in use; and that simple means is provided whereby the carriage may be quickly moved backward or forward and certain parts of the mechanism adapted for use in connection with the operation of other parts of the machine.

Having thus described my invention, I claim as new and desire to secure by Letters Patent:—

1. In a typewriting machine, the combination with a carriage, of a platen mounted on said carriage, a feed mechanism for said carriage including a vertically movable bar having teeth at the lower end thereof, key-levers, a universal bar, and a pivotally held lever engaged by said universal bar and having a tooth to engage the teeth of and move the vertically movable bar to permit the carriage to be released for letter spacing when the key-levers are depressed.

2. In a typewriting machine, the combination with a bed and a movable carriage supporting a platen adapted to travel along the bed and having a rack-bar mounted longitudinally of the carrier, of a vertical shaft, a pinion engaging said rack-bar, a rotary escapement wheel mounted on said shaft, a curved spring actuated tooth lever adapted

- 4 to engage the escapement wheel and having a vibrating lever member operatively connected with the tooth member and projecting over the carriage bed, key-levers, and a vertically reciprocating bar mounted in the main frame and operated by the key-levers to act on said vibrating lever and release the escapement wheel in its step-by-step movement.
- 10 3. In a typewriting machine, the combination with a movable carriage having a longitudinal rack-bar, of a vertical shaft, a pinion engaging said rack-bar, a rotary escapement wheel, a spring actuated tooth lever adapted to engage the escapement wheel and having a lever member operatively connected therewith, and a vertically movable bar held in the main frame and adapted to operate said lever member.
- 15 4. In a typewriting machine, a carriage for supporting the platen and movable into substantially overhanging relation to the keys, a separable rotary escapement mechanism connected to said carriage, a part of which shifts with the carriage in its compact movement, and means for operating said mechanism.
- 20 5. In a typewriting machine, the combination with key-operated levers and type operated by said levers, of a carriage, a platen mounted in the carriage and normally in the path of said type and shiftable with the carriage out of its normal position into a compact relation to another part of the typewriter to occupy less space than when in use, and a separable rotary escapement mechanism coöperating with the platen and the key-operated levers when the latter are moved to operate the platen for letter spacing, a part of said mechanism being shiftable with the platen.
- 25 6. In a typewriting machine, key-levers, type-bars operated by said levers, a carriage, a vertically movable platen mounted on the carriage and normally in the path of said type-bars and bodily shiftable forward into compact relation to another part of the typewriter to occupy less space than when in use, and a separable rotary escapement mechanism coöperating with the key-levers and operating to move the platen only when the latter is in its normal position, a part of said mechanism being shiftable with the platen and carriage in its compact movement.
- 30 7. In a typewriting machine, the combination with key-levers and type-bars operated by said key-levers, of a platen normally in the path of said type-bars and bodily shiftable into a compact relation to another part of the typewriter when not in use, and a separable rotary escapement mechanism a part only of which is shiftable with the platen and the other parts of said mechanism being independent of such shifting movement and coöperating with the key-levers to move the platen for letter spacing and only when the latter is in its normal position, said shiftable part of the escapement mechanism including a toothed rack, a pinion in mesh with the rack, a ratchet wheel and means normally in engagement with said wheel.
- 35 8. In a typewriting machine, the combination of a support, a carriage adapted to move along the support, a rack bar held to the carriage, a vertically arranged spindle supported upon the carriage bed, a pinion mounted on the spindle and engaging the rack, a ratchet wheel held on the spindle, a lever comprising two parts one of which is semi-circular and pivoted to move horizontally about the ratchet wheel and the other pivoted to move vertically, two dogs, one fixed and the other pivotally held and both carried by the horizontally pivoted part of said lever, and means for operating said escapement lever.
- 40 9. In a typewriting machine, the combination of a bed, a carriage adapted to move along the bed, a rack bar held to the carriage, a spindle supported upon the carriage bed, a pinion mounted on the spindle and engaging the rack, a ratchet wheel held on the spindle, a lever comprising two parts one of which is semi-circular and pivoted to move horizontally about the ratchet wheel and the other to move vertically, two dogs, one fixed and the other pivotally held and both carried by the horizontally pivoted part of said lever, all of which are foldable forward over the keyboard, and non-foldable key-actuated means for operating said escapement lever.
- 45 10. In a typewriting machine, the combination of a bed, a carriage adapted to move along the bed, a rack bar held to the carriage, a ratchet wheel, means engaging the rack and coöperating with the ratchet wheel, a lever comprising two parts each having a different plane of movement and carrying dogs to engage the rack, and means for operating said lever.
- 50 11. In a typewriting machine, the combination of a bed, a carriage adapted to move along the bed, a rack bar held to the carriage, a spindle supported on the carriage bed, a pinion mounted on the spindle and engaging the rack, a ratchet wheel held on the spindle, a lever comprising two parts each having a different plane of movement and carrying dogs to engage the rack, and key-actuated means for operating said lever.
- 55 12. In a typewriting machine, the combination of a vertically movable bed, a carriage adapted to move along the bed, a rack held to the carriage, a ratchet wheel, means coöperating with said wheel and engaging the rack, a lever comprising two parts one

of which is semi-circular and pivoted to move horizontally about the ratchet wheel and the other pivoted to move vertically, two dogs, one fixed and the other pivotally held and both carried by one of the pivoted parts of said lever, and means for operating said lever.

13. In a typewriting machine, the combination of a bed, a carriage adapted to move along the bed, a toothed rack held to the carriage, a pinion engaging the teeth of the rack, a ratchet wheel co-operating with the pinion, a lever comprising two parts one of which is pivoted to move about the ratchet wheel and the other to move in a different plane, two dogs, one fixed and the other pivotally held and both carried by one of the parts of said lever, and a key-actuated element for operating said lever.

14. In a typewriting machine, the combination of a bed, a carriage adapted to move along the bed, a toothed rack held to the carriage, a vertically arranged spindle supported on the carriage bed, a pinion mounted on the spindle and engaging the teeth of the rack, a ratchet wheel held on the spindle, a lever comprising two parts one of which is pivoted to move horizontally about the ratchet wheel and the other to move vertically, two dogs, one fixed and the other pivotally held and both carried by the horizontally pivoted member of said lever, all of which parts are shiftable away from the normal position of the carriage into compact relation to another part of the machine to occupy less space than when in use, and means for operating said lever.

15. In a typewriting machine, the combination of a bed, a carriage adapted to move along the bed, propelling mechanism, key-operated levers, a toothed rack movable with the carriage and fixed thereto, a spindle, a bracket in which the spindle is rotatably held, a pinion mounted upon the spindle, a ratchet wheel held to the spindle, an escapement lever comprising two parts, one part of which has a vertical movement and the other pivoted and having a movement in an arc about the ratchet wheel, a spring normally forcing the lever in one direction, two dogs, one of which is fixed and the other pivotally held and both carried by a part movable about the ratchet wheel, stops for limiting the movement of the loose dog, a spring device tending normally to prevent the ratchet wheel from moving except in one direction, and means operated by the key-operated levers for imparting movement to the two-part escapement lever to permit the carriage to move for letter spacing.

16. In a typewriting machine, the combination of a bed, a carriage adapted to move along the bed, propelling mechanism, key-operated levers, a toothed rack movable with

the carriage and fixed thereto, a spindle, a pinion held to the spindle, a ratchet wheel held to the spindle, an escapement lever comprising two parts, one part of which has a vertical movement and the other of which is pivoted and having a movement in an arc about the ratchet wheel, a spring normally forcing the lever in one direction, two dogs, one of which is fixed and the other pivotally held and both carried by the part of the lever movable about the ratchet wheel, stops for limiting the movement of the loose dog, and means operated by the key-operated levers for imparting movement to the two-part escapement lever to permit the carriage to move for letter spacing.

17. In a typewriting machine, the combination of a bed, a carriage adapted to move along the bed, key-operated levers, a toothed rack movable with the carriage and fixed thereto, a ratchet wheel, a pinion co-operating with the ratchet wheel and in mesh with the rack, an escapement lever comprising two parts each having movements in a different plane, a spring normally forcing the lever in one direction, two dogs, one of which is fixed and the other pivotally held and both carried by one part of said lever, stops for limiting the movement of the loose dog, a spring device tending normally to prevent the ratchet wheel from moving except in one direction, all of which are shiftable with the carriage from a normal working position into compact relation to another part of the machine, and independent and separable means operated by the key-operated levers for imparting movement to the two-part escapement lever to permit the carriage to move for letter spacing.

18. In a typewriting machine, the combination of a bed, a carriage adapted to move along the bed, key-operated levers, a toothed rack movable with the carriage and fixed thereto, a pinion in mesh with the teeth of the rack, a ratchet wheel, an escapement lever comprising two parts, one of which has a vertical movement and the other of which is pivoted and has a horizontal movement in an arc about the ratchet wheel, a spring normally forcing the lever in one direction, two dogs, one of which is fixed and the other loose and both carried by said lever, stops for limiting the movement of the loose dog, all of which including the carriage are foldable forward into overhanging relation to the keys to occupy less space than when in use, and means operated by the key-operated levers for imparting movement to the escapement lever to permit the carriage to move for letter spacing.

19. In a typewriting machine, the combination of a bed, a carriage adapted to move along the bed, propelling mechanism, key-operated levers, a toothed rack movable

with the carriage and fixed thereto, a spindle, a bracket in which the spindle is rotatably held, a pinion mounted upon the spindle, a ratchet wheel held to the spindle, 5 a lever comprising two parts, one of which has a vertical movement and the other of which is pivoted and has a horizontal movement in an arc about the ratchet wheel, a spring normally forcing the lever in one 10 direction, two dogs, one of which is fixed and the other loose and both carried by the part of the lever movable about the ratchet wheel, stops for limiting the movement of the loose dog, all of the parts named being 15 vertically movable and being also foldable forward into compact relation with the keyboard, and non-foldable means operated by the key-operated levers for imparting movement to the two-part escapement lever to 20 permit the carriage to move for letter spacing.

20. In a typewriting machine, the combination of a bed, a carriage adapted to travel along the bed, mechanism forming a part 25 of the escapement and adapted to permit the carriage to move for letter spacing, propelling mechanism, a vertically movable bar having teeth at the lower end thereof, key-operated levers, a universal bar adapted to 30 be operated by the said levers, an arm having a notched portion adapted to engage the universal bar and having a tooth adapted to engage the teeth of the bar whatever the 35 position of the same may be in to actuate the bar and move another part of the escapement mechanism, said bar and mechanism being separable and independent of each other, and a spring normally forcing the arm against the action of the universal 40 bar.

21. In a typewriting machine, the combination of a bed, a carriage adapted to move along the bed, a toothed rack fixed to the carriage, a spindle supported to project beneath the bed, a ratchet wheel mounted on the spindle, a spring-held clutch mechanism, 45 a member of which has a flange and normally pressed by a spring in one direction, a bracket having a part adapted to move 50 said clutch member to permit the carriage to move along its bed in one direction, said bracket having a pin on one side thereof, and a longitudinally movable bar adapted to 55 engage the pin and having a movement to raise the bracket and thereby release the clutch.

22. In a typewriting machine, the combination of a bed, a carriage adapted to move along the bed, a toothed rack fixed to 60 the carriage, a spindle supported to project beneath the bed, a ratchet wheel mounted on the spindle, a spring-held clutch mechanism, a member of which has a flange and normally pressed by a spring in one

direction, and means for operating said 65 clutch member.

23. In a typewriting machine, the combination of a bed, a carriage adapted to move along the bed, a toothed rack fixed to the carriage, a ratchet wheel, a clutch mechanism, 70 a member of which has a flange, a bracket having a part adapted to move said clutch member to permit the carriage to move along its bed in one direction, and a longitudinally movable bar adapted to 75 engage the bracket and having a movement to raise the bracket and thereby release the clutch.

24. In a typewriting machine, the combination of a bed, a carriage adapted to 80 move along the bed, a spring-held clutch mechanism forming a part of the escapement mechanism, a member of which is normally pressed by the spring in one direction, a bracket having a part adapted to move 85 said clutch member to permit the carriage to move along its bed in one direction, said bracket having a pin on one side thereof, and a longitudinally movable bar adapted to 90 engage the pin and having a movement to raise the bracket and thereby release the clutch.

25. In a typewriting machine, the combination of a bed, a carriage adapted to move along the bed, a toothed rack fixed to the 95 carriage, a spindle supported to project beneath the bed, a ratchet wheel mounted on the spindle, means engaging the teeth of the rack and coöperating with the ratchet wheel, a clutch mechanism, a bracket having 100 a part adapted to move said clutch member to permit the carriage to move along its bed in one direction, and a longitudinally movable bar adapted to engage the bracket 105 and having a movement to raise the bracket and thereby release the clutch.

26. In a visible typewriting machine having a universal keyboard, the combination of key-operated levers and type operated by said levers, a vertically movable carriage, a platen mounted in the carriage and normally in the path of said type and foldable with the carriage out of its normal position away from the type and into compact relation to another part of the typewriter to occupy less space than when in use, and a separable rotary escapement mechanism coöperating with the platen and the key-operated levers when the latter are moved to operate the platen for letter-spacing, 110 a part of said mechanism being foldable with the platen.

27. In a front-strike typewriting machine having a universal keyboard, key-levers, type-bars operated by said levers, a vertically movable carriage, a platen mounted on the carriage and normally in the path of 115 said type-bars and foldable bodily forward

into compact relation to another part of the typewriter out of the path of the type-bars to occupy less space than when in use, and a vertically movable rotary escapement mechanism coöperating with the key-levers and operating to move the platen and carriage only when the latter is in its normal position and without disturbing the relation between the key-levers and type-bars, 10 a part of said mechanism being movable with the platen and carriage in its folding movement.

28. In a visible typewriting machine having a universal keyboard, the combination 15 of key-levers and upwardly and rearward moving type-bars operated by said key-levers, a vertically movable carriage having a platen normally in the path of said type-bars and foldable bodily with the carriage 20 out of the path of the type-bars into overhanging relation to the keys when not in

use, and a vertically movable and separable rotary escapement mechanism a part only of which is foldable with the carriage and the other parts of said mechanism being independent of such folding movement and coöperating with the key-levers to move the platen carriage for letter-spacing and only when the latter is in its normal position and without disturbing the relation between the key-levers and the type-bars, said foldable part of the escapement mechanism including a toothed rack, a pinion in mesh with the rack, a ratchet wheel, and means normally in engagement with said wheel. 25 30 35

This specification signed and witnessed this 4th day of June, A. D. 1909.

C. BARTELS.

DISCLAIMER.

1,121,033.—*Otto Petermann*, New York, N. Y. FEED MECHANISM FOR TYPE-WRITING MACHINES. Patent dated December 15, 1914. Disclaimer filed October 10, 1922, by the assignee *Corona Typewriter Co., Inc.*

Hereby disclaims claim 7 of the said Letters Patent No. 1,121,033, the said claim reading as follows:

“7. In a typewriting machine, the combination with key-levers and type-bars operated by said key-levers, of a platen normally in the path of said type-bars and bodily shiftable into a compact relation to another part of the typewriter when not in use, and a separable rotary escapement mechanism a part only of which is shiftable with the platen and the other parts of said mechanism being independent of such shifting movement and cooperating with the key-levers to move the platen for letter spacing and only when the latter is in its normal position, said shiftable part of the escapement mechanism including a toothed rack, a pinion in mesh with the rack, a ratchet wheel and means normally in engagement with said wheel.”
